Patented November 15, 1904.

UNITED STATES PATENT OFFICE.

HENRIK HILLBOM, OF WALLINGFORD, CONNECTICUT, ASSIGNOR TO
R. WALLACE & SONS MFG. CO., OF WALLINGFORD, CONNECTI-
CUT, A CORPORATION.

DESIGN FOR A BACK FOR MIRRORS, BRUSHES, OR SIMILAR ARTICLES.

SPECIFICATION forming part of Design No. 37,221, dated November 15, 1904.

Application filed October 24, 1904. Serial No. 229,859. Term of patent 7 years.

To all whom it may concern:

Be it known that I, HENRIK HILLBOM, a citizen of the United States, residing at Wallingford, in the county of New Haven and State of Connecticut, have invented a new, original, and ornamental Design for a Back for a Mirror, Brush, or Similar Article; and I do hereby declare the accompanying drawing constitutes part of this specification and represents

a face view of a back for a mirror, brush, or similar article.

What I claim is—

The ornamental design for a back for a mirror, brush or similar article, as shown.

HENRIK HILLBOM.
